UNITED STATES PATENT OFFICE.

FRANK ANTHONY MAYER, OF WASHINGTON, DISTRICT OF COLUMBIA.

LOCOMOTIVE ASH PAN.

Application filed December 27, 1920. Serial No. 433,220.

To all whom it may concern:

Be it known that I, FRANK ANTHONY MAYER, a citizen of the United States, residing at Washington, D. C., have invented certain new and useful Improvements in Locomotive Ash Pans, of which the following is a specification.

This invention relates to an improved ash pan for locomotives and has as one of its 10 principal objects to provide an ash pan of this character having a rear end discharge opening and wherein said opening will normally be closed in such manner that ashes or hot coals cannot trickle through the opening onto the railway track.

The invention has as a further object to provide a locomotive ash pan pivoted at its lower margin so that the ashes can discharge from the pan only after the door has been 20 swung downwardly and rearwardly to open position.

And the invention has as a still further object to provide a locomotive ash pan wherein the ash door thereof may normally 25 be locked closed.

Other and incidental objects will appear hereinafter.

In the drawings:

Figure 1 is a side elevation showing my 30 improved ash pan in connection with the fire box and adjacent parts of a locomotive of conventional design,

Figure 2 is a vertical sectional view taken medially through the pan, this view illustrating the ash door of the pan closed,

Figure 3 is a perspective view showing the pan in detail and illustrating the ash door open,

Figure 4 is a rear end elevation of the 40 pan, parts of the locomotive being in section,

Figure 5 is a fragmentary section showing the mounting of the door brackets employed, and

Figure 6 is a fragmentary perspective view particularly illustrating the locking yoke employed in connection with the door.

In carrying the invention into effect, my improved ash pan is formed with a rearwardly and downwardly sloping bottom wall 10 to which are riveted or otherwise secured upstanding side walls 11. At its forward end margin the bottom wall is turned up to form a relatively short front wall 12 for the pan and riveted or otherwise secured to the upper margins of the side and front walls are supporting sheets 13, it being observed that the sheets which are secured to the side walls are inclined laterally outward. In Figures 1 and 4 of 60 the drawings, I have shown my improved ash pan in connection with the fire box and adjacent parts of a locomotive of conventional design and, as will be observed, the supporting sheets 13 are appropriately 65 connected with the fire box for sustaining the ash pan to hang therebeneath, the bottom wall 10 sloping rearwardly below the fire box. Preferably, brackets 14 are arranged between the side frames of the locomotive and the sheets at the sides of the pan for bracing said sheets and rigidly sustaining the pan.

Bolted or otherwise secured against the inner side faces of the side walls 11 of the 75 pan is a pair of oppositely disposed angle irons 15 sloping upwardly and forwardly from the bottom wall of the pan. At the upper ends of these angle irons is arranged a pair of oppositely disposed angle irons 16 80 which extend vertically and mounted at the upper ends of the angle irons 16 is a pair of oppositely disposed angle irons 17 which slope upwardly and rearwardly to the upper edges of the side walls. Secured to the 85 angle irons 16 and 17 is the rear end wall 18 of the pan so that this end wall is thus spaced inwardly from the rear edges of the side walls, the rear margins of the side walls providing a guard for the rear end wall. 90 This end wall terminates at the lower ends of the angle irons 16 and below the lower edge of said wall is defined a door opening. Mounted against the outer sides of the side walls 11 opposite the pair of angle irons 15, is a pair of rearwardly directed brackets 95 19. As shown in detail in Figure 5, these brackets are secured by the bolts which hold said angle irons and, at their lower end portions, the brackets are, as best seen in Figure 4, deflected laterally outward while the bracket tips are bent forwardly to overlap the deflected ends of the brackets and provide reinforced terminals extending below and rearwardly beyond the side walls of 105 the pan. Journaled upon said brackets is an ash door 21 adapted to freely fit between the side walls 11 and secured to the lower margin of said door at its outer side is a cross bar 22 upon the ends of which are 110 formed trunnions 23 and 24 extending freely through the terminals 20 of the

2

brackets. The brackets will thus support the door for rearward and downward swinging movement to open position and, as will now be noted, the bar 22 is mounted in spaced relation to the lower edge of the door so that when the door is opened the lower margin of the door will engage beneath the bottom wall 10 for limiting the door in its movement to open position. As 10 shown in Figure 3, the door will then conform to the inclination of the bottom wall, providing a continuation thereof. The door is, as best shown in Figure 2, movable to closed position seating against the angle 15 irons 15 and, at its upper margin, the door is formed with a laterally deflected lip 25 adapted to overlap the lower margin of the rear end wall 18 of the pan so that a closed joint will be formed between said 20 wall and the door as well as between the door and the side walls 11 of the pan. Further, when the door is closed, said door will abut the rear end edge of the bottom wall of the pan, so that a closed joint will 25 be formed between this wall and the door. Consequently, as will be seen, ashes within the pan cannot, when the door is closed, sift or trickle through the door opening onto the railway track.

30 As will now be observed, the trunnion 24 of the bar 22 is somewhat longer than the trunnion 23 and connected to the former trunnion at its outer end is a lever 26. Suitably secured to the adjacent side frame of 35 the locomotive is an upstanding arm 27 provided at its upper end with a rearwardly directed yoke 28, the members of which are, as particularly shown in Figure 6, formed with spaced pairs of oppositely disposed 40 openings 29. Formed in the upper end portion of the lever 26 is an opening 30 which may be brought into register with each of the pairs of openings 29 and adapted to removably engage through said 45 openings is a locking pin 31. When the ash pan is first installed the arm 27 is so positioned that, when the door 21 is closed, the opening 30 in the lever 26 will register with the outermost pair of the openings 29 in the 50 yoke 28 of said arm whereby the door may be locked closed. However, due to the terrific vibration of the locomotive as well as the excessive jolting to which the locomotive is subjected, wear upon the brackets 55 19 at the journals of the cross bar 22 and also upon the trunnions of said bar is very great. Accordingly, looseness of the door soon develops with the result that the lever 26 must be swung further rearward between 60 the members of the yoke 28 in order to close

the door. Therefore, said members of the yoke are provided with the spaced pairs of openings so that the locking pin 31 may be adjustably positioned upon the yoke to compensate for the wear upon the door 65 mounting and accordingly lock the door tightly closed. It is, of course, imperative that the door shall be maintained tightly closed in order that hot cinders may not fall from the pan onto the track and, in the absence of any arrangement whereby the locking means for the door can be adjusted, it is necessary to renew the pivotal mountings of the door. This operation requires removal of the door and thus involves expense as well as idleness of the locomotive. The door may be opened by simply removing the pin 31 and swinging the lever 26 rearwardly and downwardly and, as will be seen, the weight of any ashes retained by 80 the door will tend to facilitate opening of the door. I accordingly provide a highly efficient construction for the purpose set forth and while, in the present instance, I have shown the pan as provided with but a single door still, as will be appreciated, the pan may be readily formed with one or more additional doors, it being contemplated within the spirit of the present invention 85 that the pan may be thus modified to meet 90 the requirements of locomotives of different types.

Having thus described the invention, what is claimed as new is:

In a locomotive ash pan, the combination 95 of a body having side and bottom walls and a rear end wall and provided with a discharge opening at the rear end of the body, brackets secured to the side walls, a door, a bar secured against the door to extend thereacross and provided at its ends with trunnions journaled upon said brackets 100 swingingly supporting the door for movement to normally close said opening, a stationary arm provided at its upper end with a yoke having spaced members, a lever rigidly secured to one of said trunnions and freely movable between said members, the members being provided with spaced openings, and a locking pin engageable through 105 the openings of said members and through the lever securing the door closed, the openings in said members being adapted to receive the locking pin to hold the arm in different positions of adjustment securing the 110 door in closed position.

In testimony whereof I affix my signature.

FRANK ANTHONY MAYER. [L.S.]
